UNITED STATES PATENT OFFICE

CLINTON H. M. BULL, OF HOUSTON, TEXAS, ASSIGNOR TO REED ROLLER BIT COMPANY,
OF HOUSTON, TEXAS, A CORPORATION OF TEXAS

ANTIFRICTION DEVICE

Application filed December 27, 1927. Serial No. 242,921.

This invention relates to deep well drilling apparatus, and more particularly to drill stem anti-friction devices.

The usual drill stem comprises a number 5 of pipe sections connected together by tool joint couplings. During drilling operations, the stem moves laterally into contact with the sides of the hole, because of loose joints, bent portions, or the like, and such movement results in objectionable wear. As the stem is removed from the hole by pipe sections, the driller taps each section to discover worn portions. Badly worn pipe sections are discarded and new pipe sections used in 15 the place thereof.

This invention has for one of its objects the provision of a new and improved anti-friction device embodying means whereby it may be held in place on any part of a drill stem, to 20 prevent wear thereof, and to prevent practical resistance to the rotation thereof.

A more specific object is to provide an anti-friction device comprising separable bearing sections, and means whereby any 25 number of said sections may be grouped together on a drill stem.

Other objects will hereinafter appear.

In the accompanying drawing, which is 30 illustrative of the preferred embodiment of the invention, Fig. 1 is a fragmentary side elevation of a drill stem with the anti-friction device thereon, the device being shown in section; Fig. 2, a section on the line 2—2 of Fig. 1; Fig. 3, a detail sectional elevation of 35 the bushing; Fig. 4, a detail side elevation of the inner sleeve of a retaining device; and Fig. 5, a detail sectional elevation of the outer sleeve of a retaining device.

40 The anti-friction device includes bearing elements comprising bushing 2, collar 3, and balls 4 therebetween, the collar 3 having internal annular raceways for said balls. The bushing 2, as shown, comprises two sections, 45 and the collar 3, four sections. It is to be

understood, however, that as many of these separable sections may be used as desired.

The retaining means include an inner sleeve 5 and an outer sleeve 6. See Figs. 4 and 5. A pair of gripping plugs 7 are radially movable in sleeve 5, said plugs being held in place by a suitable ring 8. The gripping teeth on the one of said plugs is disposed of at substantially right angles to the gripping teeth on the other, so that the sleeve 5 is locked 50 against movement longitudinally of said pipe and around said pipe.

The external surface of sleeve 5 adjacent its plug openings is tapered as shown at 5a, and the inner surface of sleeve 6 is tapered as 55 shown at 6a. When the outer sleeve 6 is screwed on the inner sleeve 5, the surface 6a comes in contact with the plugs 7, said plugs being thereby forced into gripping engagement with the drill stem 1.

The sleeve 5 and bushing 2 are provided 60 with interfitting lugs 5b and 2a to prevent relative rotation thereof.

If desired, gaskets 9 may be interposed between collar 3 and sleeves 5 and 6.

As above pointed out, the bushing 2 and collar 3 may comprise any number of separable sections to cover any portion of the stem.

The sections of the collar are independently revolvable, so that should one become 75 locked on and rotate with the drill stem, the other or others will remain stationary while the drill stem rotates therein; and should any one become worn, a new one may be used in its place, the other original sections being used with the new.

By means of assembly comprising the sleeves 5 and 6 and plugs 7, the bearing elements may be held on any portion of the 80 drill stem.

The invention is not limited to the preferred embodiment shown. Various changes may be made within the scope of the following claim.

I claim:

The combination with a drill pipe of an anti-friction device having a pair of pipe gripping elements, each of said elements comprising an inner and an outer sleeve, said inner sleeve having a radial opening therein and said outer sleeve having a tapered portion adjacent said opening, and a pipe gripping plug movable in said opening and actuated by said portion when said sleeves are moved with respect to each other; a bushing between said elements; a plurality of collar sections on said bushing, said collar sections being revoluble independently of each other; and balls between each of said sections and said bushing.
